BULLDOZER BLADE AND SCOOP MOUNTING

Roy F. Smith, Silt, Colo.

Application May 27, 1952, Serial No. 290,284

3 Claims. (Cl. 37—117.5)

1

This invention relates to earth moving machinery, and in particular a bulldozer blade having mounting clamps secured to the lower edge with a bucket or scoop pivotally mounted on the blade by the clamps and also with the clamps adapted to provide mounting means for points and the like that may be extended from the edge of the blade.

The purpose of this invention is to provide means for readily mounting digging tools or elements and also earth scooping and carrying devices on the lower edge of a bulldozer blade whereby the usefulness of a bulldozer is extended.

Machinery or equipment of the bulldozer type is comparatively expensive and the average farm is not in a position to maintain various machines of this type. With this thought in mind this invention contemplates a method of converting a bulldozer blade into a digging implement or into a scoop or bucket whereby a single machine may be adapted for universal use on a farm.

A bulldozer having attachments of this type whereby the bulldozer is adapted for various types of work also converts a small tractor into a machine for universal use.

The object of this invention is, therefore, to provide attachments for a bulldozer whereby points, buckets, scoops, or the like may readily be mounted on the blade thereof.

Another object of the invention is to provide means for converting a bulldozer into a scoop or plow in which the parts are readily removable so that the blade may be used in the conventional manner.

A further object of the invention is to provide an improved plow point and scoop attachment for a bulldozer, which is of a simple and economical construction.

With these and other objects and advantages in view the invention embodies clamping members, U-shape in cross section and having ears with openings therethrough providing bearings at the ends, a scoop pivotally mounted in the bearings on the clamps, points adapted to be mounted on the blade and fluid actuated cylinders for adjusting the positions of the parts.

Other features and advantages of the invention will appear from the following description taken in connection with the drawings, wherein:

Figure 1 is a longitudinal section through the improved bulldozer blade mounting showing a scoop pivotally mounted on the lower edge of a bulldozer blade and showing cylinders for

2

adjusting the position of the scoop and elevation of the blade.

Figure 2 is a plan view of the attachment also showing a scoop mounted on a bulldozer blade.

Figure 3 is a front elevational view of a bulldozer blade with mounting clamps on the lower edge.

Figure 4 is a detail showing the lower corner of a scoop adapted to be mounted on the clamps shown in Fig. 3, with the upper part of the scoop broken away.

Figure 5 is a detail illustrating an end of one of the clamps, with other parts omitted.

Figure 6 is a detail illustrating a modification wherein a shoe is provided on the mounting frame for controlling the elevation of the blade and scoop.

Figure 7 is a front elevational view showing the lower edge of a bulldozer blade in which bolt holes are provided in the blade and illustrating a point mounted on and extended below the lower edge of the blade.

Figure 8 is a sectional plan taken on line 8—8 of Fig. 7 also showing the points on the blade.

Figure 9 is a detail showing an elevational view of one end of a blade with a point mounted thereon.

Figure 10 is a sectional plan taken on line 10—10 of Fig. 9 illustrating the position of a blade on an end of the plate.

Referring now to the drawings wherein like reference characters denote corresponding parts the improved point or scoop mounting for a bulldozer blade includes a blade 10, clamps 11 and 12, a scoop having a base 13, rear wall 14 and end walls 15 and 16, cylinders 17 and 18 for adjusting the position of the scoop and also cylinders 19 and 20 which are mounted on beams 21 and 22, respectively, for controlling the elevation of the scoop and blade.

The back of the blade 10 is provided with lugs 23 and 24 by which it is mounted on extensions 25 and 26, respectively of the beams 21 and 22, with pins 27 and 28 and the extensions are secured in position upon the beam with pins 29 and 30 which extend through openings in the extensions and also through spaced openings 31 and 32 in the beams. The opposite ends of the beams 21 and 22 are provided with yokes 33 and 34 which extend over pins 35 and 36 and which are secured in position on the pins with bolts 37 and 38, respectively. It will be understood, however, that the beams may be of other suitable design.

The clamps 11 and 12 are similar and, as shown in Fig. 5, each clamp is provided with a slot 39 for receiving the lower edge of the blade 10, ears 40 for receiving bolts 41 which attach the clamps to the blade 10, and lugs 42 which are provided with openings 43 through which pins 44 with which the scoop is pivotally mounted on the blade, extend.

With the clamps mounted on the lower edge of the blade, as illustrated in Figs. 1 and 3, the lower edges of the clamps may be used for scraping or for other purposes and different forms of tools may be mounted on the blade of the bulldozer thereby.

In the design shown in Figs. 1 and 4 the scoop is provided with hub suction 45 and 46 that extend between the lugs 42 of the clamps and through which the pins 44 extend. The lower edge of the scoop is provided with a notch 47 that is positioned over the lugs 42 at the inner ends of the clamps when the scoop is assembled on the blade.

With the parts mounted particularly as illustrated in Fig. 1 arms 48 and 49 on the rear wall 14 of the scoop are pivotally connected by pins 50 and 51 to piston rods 52 and 53, respectively, of pistons as indicated by the numeral 54 in the cylinders 17 and 18 and with pressure applied, through a tube 55 to the inner end of the cylinders 17 and 18 the upper end of the scoop is shifted outwardly, as indicated by the dotted lines in Fig. 1. The cylinders 17 and 18 are pivotally mounted by pins 56 and 57 on brackets 58 and 59, which are secured, respectively, to the beams 21 and 22.

By applying fluid under pressure through tube 55 to the inner ends of the cylinders 17 and 18 the pistons force the upper end of the scoop outwardly as indicated by the dotted lines in Fig. 1 and with the position of the valve 60 reversed the fluid under pressure is supplied through the tube 61 to the opposite ends of the cylinders whereby the upper end of the scoop or bucket is drawn against the upper edge of the blade 10.

The attachment is also provided with cylinders 19 and 20 that are mounted on the extensions 25 and 26 of the beams 21 and 22, respectively, and, as noted in Fig. 1, the cylinders are secured to the beams with bolts, such as the bolts 62 with the bolts extended through lugs 63 of the cylinders and vertically disposed webs of the beams. Fluid under pressure is supplied to the cylinders from a control valve 64 which is connected by tubes 65 to the upper ends of the cylinders and with the fluid supplied to the cylinders above the pistons 66 in the cylinders, the pistons being stationary or in fixed relation with the ground upon which the caster wheels 68 are positioned, and with the pistons in fixed relation with the ground the cylinders are forced upwardly by the fluid under pressure whereby the beams, blade and scoop are carried upwardly. The wheels 68 are pivotally mounted in the lower ends of yokes 69 which are connected to the pistons 66 with connecting rods or piston rods, as indicated by the numeral 67.

The caster yokes and wheels may be replaced with shoes as indicated by the numeral 70 and the shoes are secured to the lower ends of the connecting rods 71 with set screws 72, the connecting rods being extended from cylinders 73, similar to the cylinders 19 and 20. The cylinders 73 are mounted on the beams with lugs 74 and pins 75.

Figures 7, 8, 9, and 10 illustrate tools that may be mounted on the bulldozer blade, and in Fig. 7 a V-shape point or plow share 76 having wings 75 thereof on a tractor, a bulldozer blade carried

77 and 78 is secured with bolts 79 and 80 to the center of the blade, the bolts 79 and 80 being extended through openings provided in the blade for the bolts 41 of the clamps 11 and 12 as shown in Fig. 3.

Points 81 with upwardly extended flanges 82 are adapted to be secured to corners of the blade with bolts 83 extended through bolt holes 84 which are spaced from the ends of the blade and through which the bolts 41 at the ends of the clamps are also positioned. The points 81 are also provided with flanges 85 at the sides and, as illustrated in Fig. 10 the bulldozer blade 10 may be positioned at an angle whereby the flanges 85 are positioned parallel to the longitudinal axis of the machine. The flange 85 is supported from the flange 82 which supports 86 and it will be understood that the points may be formed of different designs and may be secured to the bulldozer blade by other suitable means.

By this means the bulldozer blade may readily be converted into a plow, digger, scoop or the like and the lower edges of the clamps 11 and 12 may be used as wearing plates that may readily be removed and replaced.

The elevation of the scoop is readily adjustable by the cylinders 19 and 20 whereby a sharp edge 87 on the bottom plate 13 may be used as a scraper and with the scoop filled with soil it may readily be elevated and the position thereof adjusted to facilitate carrying soil from one position to another. As indicated by the dotted lines in Fig. 1 the scoop may also be actuated to deposit soil or other products therein whereby soil and other products may readily be picked up, carried from one position to another and dumped.

It will be understood that modifications, within the scope of the appended claims, may be made in the design and arrangement of the parts without departing from the spirit of the invention.

What is claimed is:

1. A bulldozer blade mounting comprising a blade, spaced beams on the ends of which the blade is mounted, said blade having spaced openings therethrough and said openings spaced from the lower edge of the blade, mounting elements having scraping lower edges removably attached to said blade, a scoop pivotally mounted on said mounting elements, supporting elements mounted on and depending from said beams, means incorporated in said supporting elements for adjusting the elevation of said supporting elements and blade, and means mounted on said beams and connected to said scoop for adjusting the position of said scoop.

2. In a bulldozer blade mounting, the combination which comprises spaced horizontally disposed beams adapted to be attached at one of the ends thereof to a tractor, a bulldozer blade carried by the extended ends of the beams, clamps, U-shape in cross section and having scraping lower edges, positioned on the lower edge of the blade, a scoop pivotally mounted on said clamps, hydraulic jacks mounted on the beam and attached to the upper end of the scoop for adjusting the position of the scoop, supporting elements mounted on and depending from said beams, and means for connecting the hydraulic jacks and supporting elements to a source of fluid under pressure for actuating the hydraulic jacks and supporting elements.

3. In a bulldozer blade mounting, the combination which comprises spaced horizontally disposed beams, adapted to be mounted, at one of the ends

by extended ends of the beams, said bulldozer blade having bolt holes spaced from the lower edge thereof, clamps having blade receiving slots extended downwardly from upper edges thereof positioned on the lower edge of the blade, bolts extended through sections of the clamps and openings of the blade, a scoop pivotally mounted on said clamps, vertically positioned hydraulic jacks mounted on said beams, ground engaging elements carried by said jacks whereby the elevation of the blade is adjustable, and hydraulic jacks attached at one of the ends thereof to said beams, and at the opposite end to the scoop for adjusting the position of the scoop. 10
